United States Patent Office.

BENJAMIN S. LAWSON, OF NEW YORK, N. Y.

Letters Patent No. 90,563, dated May 25, 1869.

IMPROVED VELOCIPED.

The Schedule referred to in these Letters Patent and making part of the same.

To all whom it may concern:

Be it known that I, BENJAMIN S. LAWSON, of New York city, in the county of New York, and State of New York, have invented a new and valuable Improvement in Velocipedes; and I do hereby declare that the following is a full, clear, and exact description of the construction and operation of the same, reference being had to the annexed drawings, making a part of this specification, and to the letters and figures of reference marked thereon.

Figure 1 of the drawings is a top plan view of my device.

Figure 2 is a side view of the same.

My invention relates to velocipedes; and it consists mainly in a seat-spring of novel construction, upon which the seat is made adjustable in a novel manner.

The letter A of the drawings represents the front wheel of my velocipede, and

The letter B is the rear wheel thereof.

The letters C are cranks connected with the rear wheel in the manner shown, and

The letters D are horizontal rods connecting, the cranks C with the cranks E, next mentioned.

The letters E represent cranks, connected with the guiding-standard affixed to the front wheel, as shown, and with the rods D, as above stated.

The pedals of my velocipede are represented by the letter G. They are oval in form, and thereby adapted to the hollow of the foot.

The wheels of my velocipede have grooved peripheries, as shown at H on fig. 1.

My seat spring is shown by the letter I on fig. 2,

and the mode of its attachment to the velocipede is also thereon represented.

The letters a and c are hinges connected with said spring.

My seat is shown by the letter K, the bottom of which has a wedged form, as shown at s, and it is held upon the spring by means of the band v. The wedge-form of the bottom of the seat resting upon the spring enables the operator to adjust it upon the spring at any desired point with great ease.

The letter L represents the guiding-bar.

It will be observed that the pedals of my velocipede work above the forward wheel, and are thereby placed beyond any point of contact therewith.

It will also be observed, that owing to the peculiar arrangement of my seat, the spring or rest thereof is out of the way of the operator's feet, rendering it practicable for a lady to propel the velocipede without sitting astride of any beam or rod.

What I claim as my invention, and desire to secure by Letters Patent, is—

The seat K, having a wedged shape bottom, held by a clasp upon the spring, and adjustable on said spring by the wedge only, substantially as and for the purposes specified.

In testimony that I claim the above, I have hereunto subscribed my name, in the presence of two witnesses.

BENJAMIN S. LAWSON.
